HAIR CURLER

Benjamin W. Hendrickson, Brooklyn, N. Y.

Application April 3, 1947, Serial No. 739,092

11 Claims. (Cl. 132--37)

1.

This invention relates to a hair curling device adapted to form a curl against the head and hold the formed curl so that it may be pinned and then be separated from the device.

More particularly, this invention relates to an improvement in the device disclosed in my co-pending application, Serial No. 728,495, filed February 14, 1947.

The principal object of the present invention is the provision of an improved device of the indicated character which makes it easy and convenient for persons to curl their own hair, because it enables the ends of a strand of hair to be readily inserted and clamped preparatory to forming a curl.

The nature of the invention and its distinguishing features and advantages will appear when the following specification is read in conjunction with the accompanying drawing, in which

Fig. 1 is an underside view of a hair curler embodying the present invention.

Fig. 2 is a central longitudinal sectional view with the parts in a normal relation, the ends of a strand of hair being shown clamped preparatory to being wound to form a curl.

Fig. 3 is a fragmentary central longitudinal view showing the pivoted jaw in its open position illustrating how the hair may be readily inserted to be clamped.

Fig. 4 is a view similar to Fig. 3 showing a disengaged position of the parts for pushing or removing the formed curl from the curler separating the latter from the curl.

Fig. 5 is an end view.

The present invention provides added features to the device disclosed in the above identified application. Like the prior one, this device includes a rod or cylindrical element 10, preferably made in sections, and which is hollow. The rod 10 is longitudinally divided to provide jaws 11 and 12. The jaw 11 is fixed since it is integral with the rod 10. The jaw 12 is connected with the rod 10 by a pivot pin 13 which extends transversely of the rod and through the inner end portion of the jaw 12. This end portion 14 has a notch therein providing a shoulder 15 for a purpose to be explained. The jaw 12 thus connected is pivotally movable to an open position and a closed position with respect to the fixed jaw 11. The jaw 11 has a stepped formation at the juncture of the jaw with the rod 10 providing a shoulder 16 which is encountered by the jaw 12 thereby limiting the closing movement of the jaw 12 to a closed position in which it is parallel and in spaced relation to the jaw 11.

2.

The rod 10 has longitudinal slots 17 and 18 therein diametrically opposite each other. The slot 18 merges into a lengthwise slot 19 in the jaw 11. A hair clamping member 20 is arranged in the slot 19. A pivot pin 21 extends transversely of the rod 10 and through the inner end portion of the member 20, thus connecting the latter for pivotal movement with respect to the jaw 12 while the jaw is in its closed position. The jaw 12 is under the influence of a leaf spring 22 extending in the slot 17 and having one end secured in a notch in the rod 10 as at 23, and the other end pressing on the end portion 14 of the jaw 12 as at 24. The spring 22 functions to return the jaw 12 into its closed position. The clamping member 20 is under the influence of a leaf spring 25 extending in the slot 18 and having one end secured in a notch in the rod 10 as at 26, and the other end pressing on the end portion 14 of the jaw 12 as at 27. This end portion 27 extends obliquely in an outward direction. The spring 25 functions to move the member 20 into a clamping position to clamp the hair.

The jaws 11 and 12 provide means on one end of the rod 10 on which a strand of hair may be wound to form a curl. A slidably part 29 is arranged on the rod 10 to move along the rod as well as the jaws 11 and 12. This part 29 is tubular and embodies an enlarged circular abutment 30 which limits the axial movement of the hair along the jaws in forming a curl. The abutment 30 has a longitudinally extending groove 31 therein which receives the end portion 27. The groove 31 provides cam means 32 which coacts with the end portion 27 to move the clamping member 20 into a releasing or unclamping position in response to the outward movement of the part 29 into an advanced position, and to enable the spring 25 to move the clamping member 20 into a clamping position in response to the inward movement of the part 29 into its retracted position. The part 29 is shown in its retracted position in Figs. 1, 2 and 3, the member 20 being in its clamping position. In Fig. 4, the part 29 is shown advanced, the member 20 then being in a releasing position into which it has been previously moved by the means 32 upon the outward movement of the part 29.

The part 29 is returned to its retracted position by resilient means such as the helical spring 33 within the rod 10. One end of the spring 33 is connected with the detachable end section 34 of the rod, and the other end of the spring is connected with a cross pin 35 carried by the part 29 and extending transversely through the slots 17

and 18. The rear end walls of the slots limit the sliding movement of the part 29 to its retracted position. The springs 22 and 25 limit the outward sliding movement of the part 29 to its advanced position. The pin 35 as disposed in the slots 17 and 18 prevent the part 29 from turning on the rod assuring coaction of the cam means 32 with the end 27 of the clamping member 20.

In accordance with the invention and as an important new feature in conjunction with the pivoted jaw 12, there is provided manipulatable means which is carried by the part 29 for the purpose of moving the jaw 12 into its open position and holding it therein while the part 29 is in its retracted position. Said manipulatable means consists of an actuator 36 pivotally mounted, as at 37, on a flange 38 on the part 29. The actuator 36 is disposed in a notch in the flange 38 and extends parallel to the longitudinal axis of the rod 10 and also parallel to the slot 17. The actuator 36 has a head end 39 with a bill 40, and a tail end 41. The part 29 has a hole 42 therein to accommodate the bill 40, so that the latter may bear on the end portion 14 of the jaw 12, when the head end 39 of the actuator is manipulated with the thumb or forefinger. This will cause the jaw 12 to move into its open position as shown in Fig. 3. The abutment 30 has a small socket therein in which is arranged a small expansion coil spring 43 which presses on a ball 44. The spring 43 and the ball 44 constitute a detent. The head end 39 has a depression 45 therein which receives the ball 44 when the actuator 36 is moved into a position to open the jaw 12. Said end 39 also has a small depression 46 therein which receives the ball 44 when the actuator is moved into a position to enable the spring 22 to move the jaw 12 into its closed position. This is accomplished by pressing on the tail end 41 of the actuator 36. The detent releasably retains the actuator 36 in either of its two positions.

The abutment 30 has a segmental recess 47 therein to allow the jaw 12 to be fully opened, and the wall of the recess limits the opening movement of the jaw 12. The wall of the recess 47, or the shoulder 16, prevent the part 29 from being carelessly slid outward when the jaw 12 is open, as will appear from Fig. 3.

The clamping member 20 is mainly relied upon to exert the clamping pressure on the hair. The jaw 12 is opened by pressing on the head end 39 of the actuator 36. This enables the ends of a strand of hair to be brought between the jaw 12 and the clamping member 20 which is in a clamping position under the influence of its spring 25. The jaw 12 is moved to its closed position by the spring 22 after the actuator 36 is manipulated by pressing on its tail end 41. The member 20 clamps the hair against the jaw 12 after which the device is rotated to form a curl on the outer surfaces of the jaw 11 and 12 backed by the abutment 30. The curl is then pinned by a suitable pin. After the curl has been formed, the user while holding the rod 10 with one hand slides the part 29 along the rod 10 with the other hand from its retracted position. This causes the means 32 to cam the end portion 27, and as a result the clamping member 20 is moved outwardly on its pivot releasing the curl. At the same time the part 29 pushes or removes the curl from the jaws thereby separating the device from the hair.

By reason of the movable jaw 12 the present device may be used by persons desiring to curl their own hair, since it is easy to insert the hair when the jaw is open. The device having the

features described enables a person to easily and conveniently perform the necessary operations in making any number of curls.

I claim:

5. 1. A hair curler including a rod having a fixed jaw and a pivoted jaw on one end providing means on which hair may be wound to form a curl, a spring actuated clamping member carried by the fixed jaw which cooperates with the pivoted jaw to clamp the hair for the purpose of forming a curl, said pivoted jaw being movable between a hair clamping position and a hair unclamping position, resilient means causing the movement of the pivoted jaw into its clamping position, and manipulatable means to move the pivoted jaw into its unclamping position.
- 10 2. A hair curler as set forth in claim 1, a slideable member on the rod, said slideable member carrying the manipulatable means, cam means on said slideable member to actuate the clamping member to release the curl upon movement of the slideable member, and an abutment on the slideable member to remove the formed curl from the jaws upon continuing the movement of the slideable member.
- 15 3. A hair curler as set forth in claim 1, wherein said manipulatable means consists of a pivoted actuator in cooperative relation to the pivoted jaw.
- 20 4. A hair curler including a rod having a fixed jaw and a pivoted jaw on one end providing means on which hair may be wound to form a curl, said pivoted jaw being movable between a hair clamping position and a hair unclamping position, means on the fixed jaw to releasably clamp the hair against the movable jaw when the latter is in the clamping position, a slideable member on said rod, a manipulatable member carried by the slideable member to move the pivoted jaw into its unclamping position, resilient means to move the pivoted jaw into its clamping position, said slideable member being movable by the user with one hand while the rod is held with the other hand to remove the formed curl from the jaws.
- 25 5. In a hair curler, a rod longitudinally divided into cooperative jaws on one end on which hair may be wound to form a curl, one of said jaws pivoted to the rod for movement into an open position and a closed hair clamping position, means on the other jaw to releasably clamp the hair against the pivoted jaw when the latter is in the closed position, and an axially movable member on the rod to push the formed curl from the jaws.
- 30 6. In a hair curler, a rod longitudinally divided into cooperative jaws on one end on which hair may be wound to form a curl, one of said jaws pivoted to the rod for movement into an open position and a closed hair clamping position, means on the other jaw to releasably clamp the hair against the pivoted jaw when the latter is in the closed position, and an axially movable member on the rod to push the formed curl from the jaws when the curl is released, said means being actuated by said member to release the curl at the beginning of its movement in removing the curl.
- 35 7. In a hair curler, a rod round in cross section having an extended portion provided with a longitudinal slot and an element pivoted to the rod and combining with the extended portion to provide opposed jaws, said jaws providing means on which a strand of hair on a person's head may be wound into a curl while the ends of said strand are disposed in said slot, hair clamping means

operatively arranged in the longitudinal slot, said hair clamping means cooperating with the pivoted element clamping the ends of the strand against said element, so that the strand may be wound on said first means forming it into a curl by rotating the rod.

8. In a hair curler as set forth in claim 7, wherein said clamping means consists of a spring pressed pivoted member.

9. In a hair curler as set forth in claim 7, and a manipulatable slidable member on the rod having means which releases the clamping means and means which pushes the formed curl from the jaws upon manipulation of the slidable member.

10. In a hair curler, a rod having a fixed jaw and a pivoted jaw on one end providing means on which hair may be wound to form a curl, the fixed jaw having a longitudinal slot therein, and a spring actuated clamping member operatively arranged in said slot and pivotally connected with

the rod so as to cooperate with the pivoted jaw while the latter is in a closed position to clamp the hair for the purpose of forming a curl on said first means, said pivoted jaw being movable into an open position to facilitate placement of the ends of the strand of hair between the jaws.

11. In a hair curler as set forth in claim 6, and manipulatable means to releasably retain the pivoted jaw in the open position.

10 BENJAMIN W. HENDRICKSON.
